UNITED STATES PATENT OFFICE.

CARLES C. TRAPP, OF PORT WASHINGTON, WISCONSIN.

CHAIR OR SEAT IRON.

SPECIFICATION forming part of Letters Patent No. 431,536, dated July 1, 1890.

Application filed July 16, 1889. Serial No. 317,668. (No model.)

To all whom it may concern:

Be it known that I, CARLES C. TRAPP, residing at Port Washington, in the county of Ozaukee, State of Wisconsin, have invented 5 certain new and useful Improvements in Chair or Seat Irons, of which I do declare the following to be a full, clear, and exact description, reference being had to the accompanying drawings, forming part of this specification.

My present invention has relation more particularly to that class of irons—such as are employed upon office chairs, stools, or the like—in which the base of the chair is provided 15 with a screw-threaded bushing adapted to receive a suitable threaded spindle, by which the vertical adjustment of the chair-seat to suit the convenience of the occupant can be effected. In the construction of this class of 20 chair-irons as at present commonly practiced it is customary to attach to the spider-frame or seat of the chair a screw-threaded spindle that enters the correspondingly-threaded bushing of the base portion of the 25 chair, so that when a vertical adjustment of the chair is desired it can be effected by turning the chair-seat. This construction is objectionable, for the reason that there is constant liability to destroy the proper adjustment of the chair by the accidental turning 30 of the seat, either by the occupant himself or by others during his absence, and for the further reason that the wear upon the threaded portions of the spindle, incident to the frequent 35 turning of the chair-seat, causes a speedy loosening of the parts, thereby permitting a sagging or wobbling of the chair-seat to occur.

One object of my present invention is to 40 provide an improved construction of chair or seat iron, whereby the free turning of the chair-seat is permitted without effecting the proper vertical adjustment of the seat.

A further object of my invention is to provide 45 a chair or seat iron of such improved construction that the wear upon the screw-threaded portions of the iron, whereby the adjustment of the seat is effected, will be reduced to a minimum.

50 A still further object of my invention is to avoid the necessity of threading the main

portion of the spindle, which serves to pivotally sustain the chair-seat, and to secure a more firm and effective bearing between such spindle and the bushing of the base-frame. 55

My invention, finally, has for its object to improve in various details the construction of irons for connecting the seat and base of a vertically-adjustable chair.

With these several objects in view my invention consists in the novel features of construction and combination of parts herein-after described, illustrated in the accompanying drawings, and particularly pointed out in the claims at the end of this specification. 60 65

Figure 1 is a view in side elevation of a chair seat and base having my improved iron applied thereto. Fig. 2 is an enlarged view in central vertical section through my improved iron. Fig. 3 is a view in transverse 70 section on line 3 3 of Fig. 2.

My invention is shown as applied to one form of tilting office-chair; but it is obvious that it is equally applicable to irons for connecting the seats and bases of stools and the like. 75

A designates the seat of a chair, to the under side of which is attached a spider-frame B of ordinary construction, this spider-frame being provided with dependent arms b, to 80 which is pivotally connected, as at b', the head-piece C of the spindle D. A spring E will serve in well-known manner to control the tilting action of the chair; but as this tilting mechanism forms no part of my present invention it need not be more particularly 85 described.

Instead of forming the spindle D with screw-threads, as has been heretofore the practice, I form this spindle with a plain upper portion d, of a size adapted to fit snugly within the correspondingly-plain upper portion of the bore of the bushing F. This bushing F is provided with the usual sockets f to receive the legs, which constitute the base 95 portion of the chair. The plain part D of the spindle is formed with the lower reduced portion d', that fits within a screw H, the upper end of the screw being preferably inclined to form a seat for the correspondingly-inclined shoulder d' of the spindle. So, also, the spindle D is by preference formed at its 100

lower end with a further reduced portion d^3 , that enters the correspondingly-reduced bore h of the screw H , the upper portion of this reduced bore h being, by preference, slightly 5 concave to engage the shoulder d^4 of the spindle and form a snug bearing therefor.

In order to retain the spindle D in proper connection with the screw H , the extreme lower end of the spindle is preferably furnished with a threaded portion d^7 , that projects through the screw and is engaged with a set-nut 5. The outer face of the screw H will engage with the correspondingly-threaded lower portion g of the bushing F . The lower 15 end of the screw H is also provided with a suitable hand-wheel H' , preferably formed in one piece therewith, whereby the turning of the screw can be effected when the vertical adjustment of the chair-seat is to be had, as will 20 hereinafter more fully appear.

If desired, the spindle D may be provided with a stop or shoulder 6 near its upper portion to limit its downward movement and prevent the passage of the screw H from engagement with the bushing. 25

From the construction of parts as thus far defined it will be seen that when it is desired to effect the vertical adjustment of the chair-seat it is only necessary to turn the hand-wheel H' of the screw H , thus causing the chair-seat A to be raised or lowered to any desired extent. When the proper adjustment of the chair-seat has been thus effected, it can be maintained at the desired position by 30 means of the suitable set-screw K , that passes through a corresponding screw-threaded hole in the side of the bushing F and engages with the screw H , and by preference a portion of the screw is flattened or cut away, as at 7, to 35 afford a more secure bearing-point for the end of the set-screw K ; hence it will be seen that when the chair-seat has been adjusted to the proper position, and the set-screw K has been turned so as to bear against the 40 flattened face 7 of the screw H the further operation of the screw will be arrested, although plainly the free revolution of the chair-seat will be permitted, as the spindle D will be free to turn within the bushing F , the 45 shoulder d^2 and d^4 of the spindle bearing upon the corresponding portions of the screw. As the screw H is thus guarded against rotation during the ordinary movement of the chair, it is obvious that all wear upon its threads and 50 upon the threads of the bushing is avoided, and as the spindle D fits snugly within the plain bore of the upper portion of the bushing it is manifest that the wear between these parts will be inappreciable and all danger of 55 the lateral sagging or wobbling of the chair-seat will be guarded against. By preference the portion d of the spindle is formed of such length that the initial bearing of the spindle D upon the screw H shall occur at the shoulder d^4 , so that as the wear of the parts at this 60 point takes place the shoulder d^2 will grad-

ually be brought to bear upon the upper end of the screw H . It is plain, however, that the details of construction above set out may be varied within wide limits without departing from the spirit of my invention. 70

By the construction above defined I am enabled not only to accomplish the desired results set forth, but with this construction the parts can be very cheaply made, and when 75 set together for use will afford a far more efficient and durable means for uniting the base and seat of the chair than would be possible if the spindle were formed with screw-threads thereon from end to end in the usual 80 manner.

Having thus described my invention, what I claim as new, and desire to secure by Letters Patent, is—

1. A chair or seat iron comprising the combination, with a threaded bushing, of a spindle set within said bushing and having a plain upper portion, a vertically-adjustable screw also set within said bushing and serving to control the vertical adjustment of said spindle, and a suitable device — such, for example, as a set-screw, supplemental to said vertically-adjustable screw—for checking the movement of the adjusting-screw, and thus determining the adjustment of the spindle, 95 substantially as described.

2. A chair or seat iron comprising the combination, with a threaded bushing, of a spindle having its upper portion plain, a vertically-adjustable hollow screw provided with 100 a hand-wheel and encircling and sustaining the plain portion of the spindle, and a suitable device — such, for example, as a set-screw—for checking the movement of the adjusting-screw, substantially as described. 105

3. A chair or seat iron comprising the combination, with a bushing, of a spindle and a vertically-adjustable screw within said bushing, said screw being provided with a cut-away or flattened face 7, and a set-screw passing through said bushing for engagement with the flattened portion of the adjusting-screw, substantially as described. 110

4. A chair or seat iron comprising the combination, with a bushing having a plain bore 115 in its upper portion and a threaded lower portion, of a spindle having a plain upper portion to fit the smooth-bore portion of the bushing, and a hollow screw to engage the threaded portion of the bushing and to receive the 120 lower portion of the spindle, substantially as described.

5. A chair or seat iron comprising the combination, with a bushing, of a spindle formed with a plain portion D , having a reduced portion d' , and a hollow screw H , wherein said reduced portion d' of the spindle fits, said parts being suitably connected together, substantially as described. 125

6. A chair or seat iron comprising the combination, with a bushing, of a spindle consisting of a plain portion D , having the reduced 130

portions d' , and a hollow screw H, having a reduced bore h , and having a hand-wheel H', substantially as described.

5. A chair or seat iron comprising the combination, with a bushing having an upper plain portion and a lower threaded portion, of a spindle consisting of the plain upper portion and the reduced lower portions and

threaded portion d' , and the hollow screw H, having the hand-wheel H' and the set-nut 5, substantially as described.
